UNITED STATES PATENT OFFICE.

CASABIANCA VAN VELKINBURG, OF MORNING SUN, IOWA.

ATTACHMENT FOR LAST-JACKS.

1,174,301.

Specification of Letters Patent.

Patented Mar. 7, 1916.

Application filed March 27, 1915. Serial No. 17,449.

To all whom it may concern:

Be it known that I, CASABIANCA VAN VELKINBURG, a citizen of the United States, residing at Morning Sun, in the county of Louisa and State of Iowa, have invented certain new and useful Improvements in Attachments for Last-Jacks, of which the following is a specification, reference being had to the accompanying drawings.

This invention relates to certain improvements in attachments for last-jacks; and it is an object of my invention to provide an attachment of this general character which may be readily and conveniently applied to the standard or other part of a last-jack and serves as an effective medium whereby the accessories of the jack may be maintained in such a position as to be readily accessible to the operator.

The invention consists in the details of construction and in the combination and arrangement of the several parts of my improved attachment for last-jacks whereby certain important advantages are attained and the device is rendered simpler, less expensive and otherwise more convenient and advantageous for use, all as will be herein-after more fully set forth.

The novel features of the invention will be carefully defined in the appended claim.

In order that my invention may be the better understood, I will now proceed to describe the same with reference to the accompanying drawings, wherein—

Figure 1 is a view in side elevation of an attachment constructed in accordance with an embodiment of my invention, the coacting last-jack being shown in fragment and partly in section: Fig. 2 is a sectional view taken substantially on the line 2—2 of Fig. 1; and Fig. 3 is a sectional view taken substantially on the line 3—3 of Fig. 1.

As disclosed in the accompanying drawings, A denotes the last standard of a conventional form of last-jack and to which is clamped the arms 1—1 disposed adjacent opposite faces of the standard and herein set forth as maintained in operative position thereon through the medium of the bolt 2 disposed through said standard and the straps. The straps 1—1 have adjacent extremities projecting a predetermined distance to one side of the standard and pivotally secured therebetween through the medium of the bolt 3 is the elongated arm 4, the lower extremity whereof terminating in

an inwardly disposed extension 5 provided with a lip or projection 6 adapted to be accommodated within an aperture 7 produced in the standard. The upper extremity of the arm 4 is provided with an outward extension 8 on which rests a shelf 9 of predetermined dimensions and to further maintain said shelf in applied position, I find it of advantage to employ the straps 10 secured to said shelf and having their inner extremities provided with the offset portions 11 secured to the extension 8, in a manner which is believed to be self-evident.

Secured to the arm 4 and in predetermined spaced relation longitudinally thereof are the arms 12 arranged in substantial parallelism with the extension 8 and on which are disposed the additional shelves 14 and coacting with said arms 12 and the intermediate shelves 14 are the straps 15 to assure an increased supporting surface for said shelves 14. The shelves 9 and 14 are of predetermined dimensions and configuration but preferably of rectangular form in top plan and are engaged by the extension 8 and the arms 12 at substantially their longitudinal centers, said extension and arms being disposed transversely thereof. In order that the articles placed upon the shelves, such as lasts, blocks, and other accessories of a shoemaker, may be prevented from falling from the shelves, I provide each of said shelves along their outer longitudinal margin and end margins with the upstanding flanges 16. To further support the shelves, I also find it of advantage to connect the end portions thereof by the vertically disposed bracing rods 17.

The bottom shelf 14 is reinforced by the brace rods 18 secured to the under surface of said bottom shelf 14 adjacent the ends thereof and to the lower extremity of the elongated member 4.

From the foregoing description, it is thought to be obvious that an attachment for a last-jack constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to

the precise arrangement and formation of the several parts herein shown in carrying out my invention in practice.

I claim:

5 In combination with a standard provided with a recess, an elongated member pivotally supported by the standard at a point intermediate its length and above the recess in the standard, the lower extremity of
10 said elongated member being provided with an inwardly disposed extension, said extension having a lip adapted to enter the recess of the standard, the opposite extremity of the elongated member being provided with an oppositely directed extension, arms projecting from the elongated
15

member in predetermined spaced relation longitudinally of the elongated member and substantially parallel with the upper extension of the elongated member, shelves secured to the last named extension of the elongated member and to the arms, and reinforcing members interposed between the lower shelf and the lower extremity of the elongated member.

20 In testimony whereof I hereunto affix my signature in the presence of two witnesses.

25 CASABIANCA VAN VELKINBURG.
